FIREARM ATTACHMENT

Charles F. Trafford, Binghamton, N. Y.

Application November 1, 1943, Serial No. 508,555

6 Claims.

(Cl. 88—32)

This invention relates generally to the class of firearms and is directed particularly to improvements in devices for facilitating the aiming of the same.

In the use of firearms in warfare it is of great importance that the soldier expose himself for as short a time as possible during the sighting and firing of his weapon and the present invention has for its principal object to provide a combined periscope and telescope sight adapted to be mounted upon the side of a rifle so that either of the two instruments can be brought into working position, the periscope to be used by the soldier in locating the enemy, while keeping his own body concealed, and the telescope then used in aiming at the enemy after his position has been spotted.

Another object of the invention is to provide a combination telescope and periscope unit to be secured to the side of a rifle and mounted so that the two instruments may be rotated on an axis extending transversely of the rifle so as to bring the periscope into working position or dispose the telescope lengthwise of the rifle and in working position for use or the instruments may be turned as a unit to a position where they both extend longitudinally of the rifle in such a position that the rifle may be shouldered without discomfort to the soldier.

The invention will be best understood from a consideration of the following detailed description taken in connection with the accompanying drawing, with the understanding that minor changes or alterations may be made in the invention so long as the resultant structure does not depart from the structure defined in the appended claims.

In the drawing:

Figure 1 is a view in side elevation of the device embodying the present invention showing the same applied to a rifle.

Figure 2 is a horizontal section taken substantially on the line 2—2 of Figure 1.

Figure 3 is a vertical section taken substantially in the line 3—3 of Figure 1.

Figure 4 is a section taken substantially on the line 4—4 of Figure 2.

Referring now more particularly to the drawing the numeral 10 generally designates a rifle, upon the side of which the device embodying the present invention is mounted, in advance of the trigger guard 11.

The structure embodying the present invention comprises a base plate 12 which is secured to the side of the rifle in a suitable manner as, for ex-

ample, by the use of the ears 13 which are formed integrally with the plate and through which suitable openings are formed for the extension of securing screws 14 into suitably tapped bores in the side of the rifle.

The plate 12 has a central threaded opening 15 and three smaller openings 16 disposed adjacent the periphery of the plate and on an arc concentric therewith, two of the openings 16 being arranged in a line extending lengthwise of the rifle and the third being disposed mid-way between the first two below the opening 15.

The numeral 17 designates the top or rotatable plate. This latter plate is provided with a central opening 18 and is of substantially the same diameter as the plate 12 over which it positions. A pivot screw 19 passes through the opening 18 and is threaded in the opening 15 of the bottom plate, the head overlying the outer face of the rotatable plate 17 to maintain it in position but permitting it free rotation.

Extending radially across the top plate 17 is a strap spring 20 which is secured permanently at 21 to the rotatable plate 17 adjacent the periphery thereof and extends across the screw to and beyond the edge of the plate remote from the securing means 21 forming the extended end 22 which is designed to be used as a finger piece or lip to facilitate flexing the spring outwardly away from the plate 17. Intermediate its ends the spring 20 is off-set as indicated at 23 so as to be free from contact with the pivot screw 19 across which it extends.

The rotatable plate 17 has an aperture 24 therethrough beneath the free end of the spring 20 and centered the same distance from the radial center of the plate as the openings 16.

Adapted for extension through the opening 24 and for engagement in one of the openings 16 of the fixed bottom plate, is a holding stud 25 which is carried by the spring 20.

Secured in spaced parallel relation to the outer face of the rotatable plate 17, with the spring 20 therebetween and parallel therewith, are the two instruments 26 and 27 which are respectively a telescope and a periscope. The telescope is secured substantially mid-way between its ends to the rotary plate while the periscope is secured to this plate at one side of its transverse center and the lateral extension 28 at the end of the periscope remote from the rotatable plate, is disposed beyond the eye piece end 29 of the telescope and directed across the telescope while the oppositely directed lateral extension 30 of the periscope is inwardly of the sighting end of the tele-

scope and is directed away from the telescope as shown.

In the use of the present device the retaining spring 20 is flexed outwardly to disengage the stud or keeper pin 25, if the instruments are disposed lengthwise of the rifle, so that the plate and the instrument carried thereby may be rotated in the correct direction to move the securing stud 25 down to the lower hole 16. This will bring the periscope upright in front of the telescope with the lateral extension 30 of the periscope directed forwardly. The user of the gun can then look over the surrounding territory by peering into the lower end of the periscope, while keeping his body under cover. After the quarry has been located the spring latch is released and the plate turned so as to bring the telescope to uppermost position parallel with the rifle barrel. The user of the rifle can then quickly rise from his position and sight the rifle through the telescope at the quarry previously located. By this means only a few seconds is required to aim and fire the rifle, the user thereby avoiding exposing himself to enemy fire for any length of time as would be necessary for him to do it if he did not have the periscope as an aid in locating the quarry before he exposes himself to the enemy's view.

I claim:

1. The combination with a shoulder rifle of a telescope including a straight tube having coaxial lenses in its ends and a periscope including a straight tube terminating at its ends in oppositely directed right angular portions, supported as a unit in parallel relation upon the side of the rifle for rotation together on an axis extending transversely of the rifle for selective disposition in position for sighting in the direction in which the rifle is aimed.

2. The combination with a shoulder rifle, of a telescope including a straight tube having coaxial lenses in its ends and a periscope including a straight tube terminating at its ends in oppositely directed right angular portions, the telescope and periscope being connected together in parallel relation, and means for mounting the unit upon the rifle and for moving the unit upon the mounting for the selective disposition of the telescope and periscope in working position with respect to the barrel of the rifle.

3. The combination with a shoulder rifle, of a plate adapted to be secured to one side of the rifle, a second plate pivotally attached to the first

plate for rotation on an axis extending transversely of the barrel of the rifle, a telescope including a straight tube having coaxial lenses in its ends and a periscope including a tube terminating at its ends in oppositely directed right angular portions, secured in fixed parallel relation to the second plate to be rotated thereby for bringing the telescope into parallel relation with the rifle barrel and for bringing the periscope into a vertical position perpendicular to the barrel, and a shiftable latch means connecting the plates together for securing the second plate in a selected position with respect to the first plate.

4. A combination structure as set forth in claim 3, in which said latching means comprises a resilient spring member secured to the outer face of the second plate and having a portion extended across the periphery of the plate and a pin carried by the spring member for extension through an aperture in the second plate and for selective engagement in underlying apertures in the first plate.

5. A unit of the character stated, comprising a plate body, means for securing the body to a support, a second plate overlying the first plate, means coupling the second plate with the first plate for rotation of the second plate relative to the first plate, a telescope including a straight tube having coaxial lenses in its ends and a periscope including a straight tube terminating at its two ends in right angle oppositely directed portions secured in parallel relation to and across the face of the second plate, an end portion of the periscope being disposed beyond the adjacent end 35 of the telescope and directed toward the axial center of the telescope whereby the view through the said end portion of the periscope will not be interrupted by the adjacent telescope, and a latching connection between the plates for securing the second plate in a selected working position when rotated with respect to the first plate.

6. A unit as set forth in claim 5, in which said latching connection comprises a leaf spring disposed across the outer face of the second plate 45 and secured thereto at one end and having its other end extended across the periphery of the second plate, and a pin carried by the leaf spring adjacent to said other end and adjacent the periphery of the second plate for extension through an opening in the second plate and engagement in a keeper opening in the underlying first plate.

CHARLES F. TRAFFORD.
